GENERAL RUBBER COMPANY, A CORPORATION OF NEW JERSEY.

PROCESS AND APPARATUS FOR TREATING LATEX.

1,268,638.

Specification of Letters Patent

Patented June 4, 1918.

Application filed February 28, 1917. Serial No. 150,386.

To all whom it may concern:

Be it known that I, EDWARD MARK SLOCUM, a citizen of the United States, residing at Medan, Province of Deli, Sumatra, 5 Dutch East Indies, have invented certain new and useful Improvements in Processes and Apparatus for Treating Latex, of which the following is a full, clear, and exact description.

10 This invention relates to apparatus and processes for treating latex or similar material and more particularly to an apparatus and process for treating latex during coagulation adapted to provide a coagulum 15 having any desired shape.

One of the objects of the invention is to provide an apparatus of the kind described capable of treating large quantities of latex in a small area. Another object of the invention is to provide a simple and efficient 20 apparatus of the kind mentioned adapted to produce a dense coagulum.

Another object of the invention is to provide a process of the kind described for preparing easily handleable continuous lengths 25 of coagulum.

Another object is to provide a process of the kind mentioned for producing a dense compressed coagulum.

30 Briefly, the apparatus consists of a chamber for coagulating latex and means in the chamber to provide a coagulum having any desired shape.

In the accompanying drawing wherein 35 one of the possible embodiments of apparatus forming part of my invention is shown,

Figure 1 is a plan view thereof; and

Fig. 2 is a sectional elevation thereof 40 taken on the line 2—2 of Fig. 1.

Referring now more specifically to the drawing the numeral 1 indicates a substantially cylindrical tank of steel or other material interiorly tinned and adapted to resist pressure, which serves as a chamber in which coagulation of latex or similar material may take place. The top of the chamber is provided with a cover 2 preferably also of steel tin-lined and provided with 45 radially disposed reinforcing I-beams 3 adapted to strengthen the top to resist pressure resulting from coagulation.

The cover is adapted to be held in place by means of a series of pivoted bolts 4 secured to the sides of the chamber 1 adjacent the top thereof. These bolts pass through notches 5 and 6 formed respectively in the edge of the cover 2 and in the lip 7 projecting from the cylinder 1. They are held in place by nuts 8 contacting with the face 60 of cover 2 adjacent the notches 5.

Preferably to the under side of the cover 2 is attached a device for shaping the coagulum into a continuous strip. As here shown it consists of a spiral partition 9 65 rolled on itself and providing spaces between successive convolutions having its center supported by an upright pin 10 attached substantially centrally to the cover 2. The walls of the partition are attached 70 to the under side of the cover 2 by spaced brackets 11. The spiral partition extends preferably for the entire height of the chamber 1 and makes a tight fit with the bottom thereof. It is also preferably made 75 of steel provided with an exterior covering of tin.

The apparatus has been found capable of treating large quantities of material in a small area and has proved simple and 80 efficient in use. The tank 1 may be made in any desired shape, for example, either oval or square, with or without rounded corners, in accordance with the desired shape of the coagulum. It will, of course, be understood 85 that the spiral partition may be replaced by partitions of other forms, although the spiral form is preferred in view of its simplicity and the great length of coagulum strip which may be obtained by its use. A 90 spiral like that shown in the drawing having an extreme diameter of approximately thirty feet will produce a strip of approximately three hundred feet. Further the partition may or may not be secured to the 95 cover and may be removably or otherwise secured in the tank.

It will also be noted that the tank may be made gas-tight and under these circumstances coagulation may be conducted under 100 the pressure of any desired gas or similar agent. It will be understood that although the chamber 1 as here shown is stationary it may be mounted on any suitable vehicle.

For example, the tank of a tank-car may constitute the chamber 1, in which may be placed a spiral partition and coagulation allowed to take place during the transit of 5 the material.

It will also be noted that the partition may be sectional or otherwise. In case a sectional partition is provided a spindle is placed in the middle of the tank and when 10 coagulation is complete the coagulum is lifted out of the tank and the ends of the spindle are engaged by a suitable frame so that the coagulum may be rotated about its center. The strip is then reeled out, the 15 partition-segments or-sections being removed as freed by the winding off of the coagulum strip.

The process constituting part of my invention briefly consists in coagulating latex 20 and shaping it during coagulation as a continuous strip. The process may be carried out by the apparatus above described, although any desired type of apparatus may be employed.

25 In its preferred form the process consists in introducing the latex of *Hevea Brasiliensis*, or similar latex adapted to expand upon coagulation into a suitable chamber such as the chamber 1 shown in the drawings, preferably filling the latter to a point where, when the cover 2 with its spiral is put in place, the latex will completely occupy the interior. Coagulation is then allowed to take place, the spiral partition coöperating 30 with the bottom wall and cover 2 and serving to shape the latex during coagulation. In latices of the character of *Hevea* which are adapted to expand when coagulated, the force of the coagulation expansion is preferably employed to provide a dense compressed coagulum. This is accomplished by securing the cover 2 in place by means of the bolts 4, whereby the expansion will be counteracted by the walls of the chamber 35 40 and a fixed volume of coagulum will result.

It will be understood that coagulation may be allowed to take place with or without the addition of various modifying agents, such as accelerators, retarding agents, 50 antiseptics, etc. Sulfur or other vulcanizing agent may be added prior to coagulation or subsequent thereto, or at any other time prior to vulcanization.

The coagulum resulting from the process 55 appears as an easily handleable continuous strip, which lies in the tank upon removal of the spiral partition as a laminated roll constituting a mass substantially solid along both axes. The coagulum in view of the 60 pressure exerted thereon is also dense and finely grained.

As many apparently widely different embodiments of this invention may be made without departing from the spirit thereof,

it is to be understood that I do not intend 65 to limit myself to the specific form of the invention as set forth except as indicated in the appended claims.

Having thus described my invention, what I claim and desire to protect by Letters Pat- 70 ent is:

1. In an apparatus of the kind described, in combination, a chamber for coagulating latex, and stationary means coöperating with a wall of said chamber to provide a con- 75 tinuous strip of coagulum.

2. In an apparatus of the kind described, in combination, a chamber for coagulating latex, and means coöperating with a wall of said chamber to provide a substantially 80 spiral strip of coagulum.

3. In an apparatus of the kind described, in combination, a chamber for coagulating latex, and a partition extending substantially throughout the chamber and seated 85 against a wall of the chamber to provide a continuous strip of coagulum.

4. In an apparatus of the kind described, in combination, a chamber for coagulating latex, and a rolled partition therein providing 90 spaces between successive convolutions.

5. In an apparatus of the kind described, in combination, a chamber for coagulating latex, a cover therefor, means to secure the cover in place, and a partition in said chamber coöperating with a wall thereof to provide 95 a strip of coagulum.

6. In an apparatus of the kind described, in combination, a chamber for coagulating latex, a cover therefor, and a rolled partition 100 providing spaces between successive convolutions in said chamber.

7. In an apparatus of the kind described, in combination, a chamber for coagulating latex, a cover therefor, means to secure the 105 cover in place, and a spiral partition attached to said cover and extending substantially the entire height of the chamber.

8. A process of the kind described which comprises coagulating latex into a substantially solid mass and shaping the mass during coagulation by partition walls as a substantially continuous strip. 110

9. A process of the kind described which comprises coagulating latex, and shaping 115 it during coagulation as a laminated roll.

10. A process of the kind described which comprises coagulating latex into a substantially solid mass and shaping the mass during coagulation as a substantially continuous 120 strip by a spiral partition wall.

11. A process of the kind described which comprises confining latex between a form and the wall of a container inclosing the form, and coagulating the latex. 125

12. A process of the kind described which comprises introducing latex into a chamber containing a rolled partition providing

spaces between successive convolutions, and coagulating the latex in the chamber about the partition.

13. A process of the kind described which comprises coagulating latex, and shaping it under pressure during coagulation as a strip.

14. A process of the kind described which comprises coagulating latex, and shaping it under pressure during coagulation as a laminated roll.

15. A process of the kind described which comprises introducing latex adapted to expand upon coagulation into a chamber containing a form adapted to produce a strip, coagulating the latex in the chamber about the form, and fixing the volume of the resultant coagulum.

16. A process of the kind described which comprises introducing latex adapted to expand upon coagulation into a chamber containing a spiral partition, coagulating the latex in the chamber about the partition, and fixing the volume of the resultant coagulum.

17. A process of the kind described which comprises coagulating latex into a substantially solid mass, shaping the mass during coagulation by partition walls as a substantially continuous strip and adding a vulcanizing agent thereto.

18. A process of the kind described which comprises coagulating latex, shaping it during coagulation as a laminated roll, and adding a vulcanizing agent thereto.

19. A process of the kind described which comprises coagulating latex into a substantially solid mass, shaping the mass during coagulation as a substantially continuous strip by a spiral partition wall and adding a vulcanizing agent thereto.

20. A process of the kind described which comprises confining latex between a form and a wall of a container inclosing the stationary form, coagulating the latex and adding a vulcanizing agent thereto.

21. A process of the kind described which comprises introducing latex into a chamber containing a rolled partition, providing spaces between successive convolutions, coagulating the latex in the chamber about the partition, and adding a vulcanizing agent thereto.

22. A process of the kind described which comprises coagulating latex, shaping it under pressure during coagulation as a strip, and adding a vulcanizing agent thereto.

23. A process of the kind described which comprises coagulating latex, shaping it under pressure during coagulation as a laminated roll, and adding a vulcanizing agent thereto.

24. A process of the kind described which comprises introducing latex adapted to expand upon coagulation into a chamber containing a form adapted to produce a strip, coagulating the latex in the chamber about the form, fixing the volume of the resultant coagulum, and adding a vulcanizing agent thereto.

25. A process of the kind described which comprises introducing latex adapted to expand upon coagulation into a chamber containing a spiral partition, coagulating the latex in the chamber about the partition, fixing the volume of the resultant coagulum, and adding a vulcanizing agent thereto.

Signed at New York, County and State of New York, this 8th day of February, 1917.

EDWARD MARK SLOCUM.
